(Cl. D49—35)

FIG - 5

FIG - 7

FIG - 8

FIGURE 1 is a perspective view of a cover for a litter receptacle, showing my new design;

FIGURE 2 is a top plan view of the design;

FIGURE 3 is a front elevational view thereof;

FIGURE 4 is a bottom plan view thereof;

FIGURE 5 is a perspective view of a modified form of a cover for a litter receptacle showing my new design;

FIGURE 6 is a top plan view of the design of FIGURE 5;

FIGURE 7 is an elevational view of the design of FIGURE 5; and

FIGURE 8 is a bottom plan view of the design of FIGURE 5.

The broken line showings of litter receptacles in FIGURES 1 and 5 are for illustrative purposes only.

This application is a continuation of my earlier pending applications Serial Nos. D-87,152 and D-87,796 filed Sept. 24, 1965 and Oct. 22, 1965, respectively, both of which are now abandoned.

I claim:

The ornamental design for a cover for a litter receptacle, as shown and described.
